CLAIM

The ornamental design for a bait protector, as shown and described.

DESCRIPTION

FIG. 1 is an upper right front perspective view of a bait protector.

FIG. 2 is a lower left front perspective view of the bait protector as shown in FIG. 1.

FIG. 3 is a front view of the bait protector as shown in FIG. 1.

FIG. 4 is a rear view of the bait protector as shown in FIG. 1.

FIG. 5 is a right view of the bait protector as shown in FIG. 1.

FIG. 6 is a left view of the bait protector as shown in FIG. 1.

FIG. 7 is a top view of the bait protector as shown in FIG. 1; and,

FIG. 8 is a bottom view of the bait protector as shown in FIG. 1.

The broken lines are for illustrative purposes only and form no part of the claimed design.

1 Claim, 8 Drawing Sheets
